UNITED STATES PATENT OFFICE.

FRANK D. WOODLOCK, OF ST. LOUIS, MISSOURI.

READING DEVICE.

1,115,144.

Specification of Letters Patent. Patented Oct. 27, 1914.

Application filed October 8, 1912. Serial No. 724,679.

To all whom it may concern:

Be it known that I, FRANK D. WOODLOCK, a citizen of the United States, and residing at St. Louis, in the State of Missouri, have 5 invented certain new and useful Improvements in Reading Devices, of which the following is a specification.

This invention relates to devices useful for the purpose of facilitating reading.

10 Books, etc., as now printed use type of a size which is frequently too small and thereby causes abnormal strain on the eyes of the reader. It is not desirable to make the type too large as this will unduly increase the 15 bulk of the book. Some readers use magnifying reading glasses but these are inconvenient as they have to be moved over the printed pages.

One of the objects of this invention therefore is to construct a device in which the 20 printed matter can be small so as to keep the bulk of the printed matter within bounds, and to provide means whereby this printed matter is magnified when exposed to the 25 reader.

Another object is to construct a device in 30 which the printed matter may be placed on a continuous sheet or web so as to facilitate the printing thereof and do away with the binding which is necessary in books as now constructed.

Further objects will appear from the detail description taken in connection with the accompanying drawings, in which:

35 Figure 1 is a plan view of a device embodying this invention, Fig. 2 is a section on the line 2—2 Fig. 1, Fig. 3 is a section on the line 3—3 Fig. 1, Fig. 4 is a section on the line 4—4 Fig. 1, Fig. 5 is an enlarged section 40 on the line 5—5 Fig. 3, Fig. 6 is a section showing another form of this invention, parts being shown in elevation. Fig. 7 is an enlarged detail view of the parts shown in Fig. 6, Fig. 8 is an enlarged section on the line 8—8 Fig. 9, and Fig. 9 is a detail plan 45 view of the lower left hand corner of the device.

Referring to the accompanying drawings and more particularly to Figs. 1 to 5 inclusive, 50 10 designates a support or casing which may be in the form of a book. This casing is provided with a cover 11, hinged at 12. The support or casing and its cover may be constructed of any suitable material such as 55 paper, fiber, or even a light metal like alu-

minum, and may be bound like an ordinary book.

A pair of strips 13 and 14 extend longitudinally of the casing, and these strips are slotted as shown at 15 to provide vertical 60 guideways for U shaped bearing blocks 16 supported on springs 17 and adapted to receive the pintles 18 and 19 of a pair of rolls 20. The pintles 19 extend through slots 21 in the sides of the casing and are provided 65 with knurled heads 22 positioned outside of the casing. The pintles 18 form a permanent part of the rolls but the pintles 19 are each provided with a squared portion 23 having a removable connection with the roll. 70 The fit between the pindle 19 and the roll is however tight enough to hold the pindle in position when inserted in the roll. The rolls 20 are adapted to receive a sheet or web 24 of paper or other suitable material, and the web passes from one roll to the other and is held against the bottom of the cover by means of suitable guide rods 25 mounted on the strips 13 and 14. The web is narrowed 75 down at its ends as shown at 26 so as to slip 80 into slots in the rolls in order to secure the web to the rolls in a manner well known to those skilled in the art.

The cover 11 is cut away as shown in Fig. 1 so as to provide a large opening or window 85 in the cover above the web as positioned and guided by the guide bars. A lens 27 is positioned in this window in any suitable manner, as by grooving the inside edges of the window, the edges of the lens fitting the 90 grooves. This lens may be of any suitable construction; in this particular instance it is of the plano-convex type, but it may be of the ordinary double convex type. Its purpose is to magnify the exposed portion of 95 the sheet or web which is positioned underneath the window and underneath the lens mounted in the window. The focal length of this lens is preferably made small and this lens is so positioned with respect to the sheet or web 24 that the printed-matter thereon will be magnified. A clasp 28 of 100 any suitable construction is adapted to hold the cover closed.

The rolls 20 can be removed and replaced 105 when the cover is open. The reading matter will be furnished in the form of a web rolled on one of the rolls. In order to place the device in condition for reading, the roll having the web thereon is placed in the lower 110

end of the casing and the web is passed over the guide bars 24 and its end 26 is attached to the upper roll. The cover is then closed and secured by means of the clasp 28. The 5 lens will magnify the printed matter on the sheet or web so that the reader can easily read the same. When the reader has finished the part exposed below the window and the lens (which we may call the first 10 page) the knurled head 22 is turned to wind up the web on the upper roll and roll it from the lower roll so as to expose another portion of the web. Successive portions of the entire web can be thus read. The web can 15 have an entire novel or an article or a series of articles or other reading matter printed thereon. The type can be made small since it can be magnified to any suitable extent, a large amount of printed matter can thus 20 be placed on a web of comparatively short length. This web can on the other hand be made very thin so that a web of considerable length can be placed on a roll and in a casing of comparatively small size. In the 25 manufacture of books the reading matter is printed on a web and this web is cut up into pages. This latter operation requires considerable extra work and also requires considerable care in the spacing of the printed 30 matter on the different pages. In accordance with this invention however the web can be used as it comes from the press. It is necessary to hold the sheet or web a predetermined distance from the lens in order 35 to obtain a clear focus, and this predetermined distance must be maintained as the web is rolled up and passes from one roll to the other. For this purpose the rolls are 40 yieldingly supported so that the web will be at all times maintained against the lower face of the cover and thus a predetermined distance from the lens.

In the construction shown in Figs. 1 to 5 inclusive the sheet or web is moved by 45 hand. It is however possible to provide automatic means for accomplishing this. Such a construction is shown in Figs. 6 to 50 9 inclusive in which parts which are similar to those shown in Figs. 1 to 5 inclusive are designated by the same reference characters. The web has rolls supported in the same manner as in Figs. 1 to 5 inclusive but the cover is in this case hinged at a point slightly nearer the right hand edge of the 55 casing as shown at 12 Fig. 9. The lens and its mounting are however the same as in Figs. 1 to 5 inclusive.

The pintles 30 have square ends adapted to engage square sockets 31 on the ends of 60 a pair of flexible shafts 32. These flexible shafts are connected to and supported by bevel gears 33 and 34 mounted in a supporting strip 35 secured to the side wall of the casing 10. A shaft 36 is supported in bearings 37 on the strip 35, and this shaft is pro-

vided with bevel gears 38 and 39 adapted to mesh with the bevel gears 33 and 34 respectively. A torsional spring 40 is mounted on the shaft 36 and has one end thereof connected with the upper bearing 37 and the other end thereof connected with a collar 41 rigidly connected to the shaft. A second collar 42 is rigidly connected to the shaft, and a loose collar 43 between the collars 41 and 42 is provided with a pin 44 passing 75 through a slot 45 in a lever 46. This lever 46 is made of thin spring material and is normally moved in a left hand direction Fig. 9 toward the offset portion 49 of the slot 48 in the plate 47, whereby the lever will be normally held in this offset portion. The collar 41 is provided with pins 50 engaging a lug 51 on the strip 35. The sides of this lug are beveled as shown in Figs. 6, 7 and 8 so as to provide inclined faces 52. 80 The hub 53 of the bevel gear 33 is provided with an angular socket adapted to receive a key 54.

When the lever 46 is in position shown in Fig. 8 and in engagement with the offset portion 49, the shaft 36 will be positioned so as to maintain the gears 38 and 39 out of engagement with the gears 33 and 34. One of the pins 50 will at this time engage the lug 51 so as to prevent rotation of the shaft 36 under the tension of the spring 40. If now the lever 46 is moved to the position shown in Fig. 9 the shaft 36 will be moved longitudinally so as to throw the gear 38 into mesh with the gear 33 and at the same time release the pin 50 from the lug 51. The shaft 36 is now released and will be rotated by the spring 40 so as to rotate the upper roll 20 in a direction to wind up the sheet or web from the lower onto the upper roll. The inclined face 52 will cause the pins 50 to ride down gradually and this face will act as a brake to brake the movement of the shaft 36. The rapidity of winding can therefore be controlled by gradually moving the lever 46 from its central position to its extreme position.

When the lever is at its extreme position the pins 50 will be entirely clear of the lug so that the shaft 36 can revolve freely. By keeping the pins slightly in engagement with the inclines 52 the movement of the shaft 36 can be braked. The slot 45 is made slightly longer than the diameter of the pin 44 so that the pins 50 will slide off of the incline when the lever 46 is nearly in its extreme position. As soon as the correct amount of the web has been wound up the lever 46 is moved back to central position so as to disconnect the gear 38 from the gear 33 and this will in turn move the collar and the pins 50 thereon into the path of the lug 51 so as to arrest the movement of the shaft 36. The parts are so constructed that the shaft will be stopped before the gears 130

38 and 33 move completely out of mesh. In order to reverse the direction of the movement of the web the handle 46 is moved rearwardly (or downwardly in Fig. 9) and this will cause the gear 39 to mesh with the gear 34 so as to rotate the lower roll 20. The braking action of the pins 50 and the lug 51 is similar in this case. When the handle 46 is moved back to central position 10 it will snap into the offset portion 49 and lock the shaft 36 in normal position with the gears 38 and 39 thereon out of mesh with the gears 33 and 34 respectively. In order to wind the spring 40 the handle 46 is moved 15 to the position shown in Fig. 9 to throw the gears 38 and 33 into mesh, turning of the key 54 will now wind the spring. This will, of course, rotate the upper flexible shaft 32, but since the upper roll 20 can, at this time, 20 be removed, this roll will not be rotated. The rolls can be readily removed and replaced since the ends of the pintles 30 are adapted to readily connect with and disconnect from the sockets 31 in the flexible 25 shafts 32. These flexible shafts will permit either upward or downward movement of the rolls as the web is wound and unwound therefrom.

It is obvious that various changes may be 30 made in the details of construction without departing from this invention within the scope of the appended claims, and it is therefore to be understood that this invention is not to be limited to the specific constructions shown and described.

Having thus described the invention what is claimed is:

1. A reading device comprising a casing, a cover hinged on said casing, a lens mounted in said cover, a pair of rolls adapted to receive a printed sheet, said rolls being mounted in said casings for movement toward and from said cover, springs for sustaining said rolls, constructed to permit said 40 rolls to automatically adjust themselves with respect to said lens as the sheet rolls from one roll to the other, and a series of guide rods extending across said casing in the space between the rolls and arranged directly underneath said lens and underneath the sheet, adapted to constantly maintain the sheet between the rolls in a predetermined position underneath said lens, to cause said lens to expose and magnify the 50 printed matter on the sheet, said rolls and sheet being maintained in position by said cover when closed, and being removable when said cover is open.

2. A reading device comprising a casing, a lens mounted on said casing, a pair of rolls in said casing adapted to re-

ceive a printed sheet together with means for automatically maintaining said rolls and the sheet between said rolls in a position with respect to said lens to cause said lens 65 to expose and magnify the printed matter on the sheet, and operating means having a flexible connection with one of said rolls.

3. A reading device comprising a casing, a lens mounted on said casing, a pair of 70 rolls in said casing adapted to receive a printed sheet together with means for automatically maintaining said rolls and the sheet between said rolls in a position with respect to said lens to cause said lens to 75 expose and magnify the printed matter on the sheet, including means for adjustably supporting one of said rolls in said casing, and operating means on said casing having an automatically adjustable connection with 80 said roll.

4. A reading device comprising a casing, a lens mounted on said casing, a pair of rolls in said casing adapted to receive a printed sheet together with means for automatically 85 maintaining said rolls and the sheet between said rolls in a position with respect to said lens to cause said lens to expose and magnify the printed matter on the sheet, and driving means having flexible 90 driving connections with said rolls.

5. A reading device comprising a casing, a lens mounted on said casing, a pair of rolls in said casing adapted to receive a printed sheet together with means for automatically 95 maintaining said rolls and the sheet between said rolls in a position with respect to said lens to cause said lens to expose and magnify the printed matter on the sheet, including means for removably and adjustably supporting one of said rolls in said casing, and driving means having a removable and flexible driving connection with one of said 100 rolls.

6. A reading device comprising a casing, a lens mounted on said casing, a pair of rolls in said casing adapted to receive a printed sheet together with means for automatically maintaining said rolls and the sheet between 105 said rolls in a position with respect to said lens to cause said lens to expose and magnify the printed matter on the sheet, including means for removably and adjustably supporting said rolls in said casing, and driving means having removable and 110 flexible driving connections with said rolls.

In testimony whereof I affix my signature in the presence of two witnesses.

FRANK D. WOODLOCK.
